[57] CLAIM

The ornamental design for a garden caddy, as shown
and described.

DESCRIPTION

FIG. 1 is a front elevational view of the garden caddy
showing my new design;

FIG. 2 is a rear elevational view thereof;

FIG. 3 is a right side elevational view thereof at a re-
duced scale, the left side elevational view being the
mirror opposite thereto;

FIG. 4 is a top plan view thereof at the same scale as
FIG. 3; and,

FIG. 5 is a perspective view thereof.
